TYPOGRAPHICAL COMPOSING AND
DISTRIBUTING MACHINE

Richard Henry Scott, Enfield, England, assignor
to Linotype and Machinery Limited, London,
England, a limited liability company of Great
Britain

Application March 23, 1939, Serial No. 263,623
In Great Britain March 31, 1938

6 Claims. (Cl. 199—34)

This invention relates to typographical composing and distributing machines, such as, for example, those known commercially under the registered trade-mark "Linotype", wherein typographical elements stored in a magazine are released therefrom in order of composition, assembled in line, and subsequently passed through a distributing mechanism by which they are returned to the respective channels of the magazine.

In the operation of such machines a requirement frequently arises, for the insertion in the composed line, by hand, of elements not stored in the magazine, for example, elements for the production of characters of special fonts, or head letter or display characters, and on distribution such elements are ordinarily passed through the distributing mechanism, which comprises a ribbed bar engaged by teeth on the elements to a pie chute which conducts them, on release from the bar, to a special receptacle such as a pie stacker or pie bowl.

One form of pie chute commonly employed is tubular and guides the elements mainly by their leading and following faces; consequently, if thin elements have to pass through a tube large enough to accommodate the thickest head letter elements, they are liable to tilt and jam in the chute. This difficulty is avoided by the use of another known form of chute constituted by a channelled member open at the forward side, which guides the elements mainly by the engagement of their laterally extending ears within channels on opposite sides of the chute, with the following faces of the elements abutting against the closed wall of the chute. The usefulness of this form of chute, however, is restricted inasmuch as the ears of the elements which are to be guided therein must be located at a substantially uniform distance from the following face of the element, the variations in thickness being at the forward side of the said ears, so that the bodies of the elements can extend forwardly through the open side of the chute.

Various fonts of elements at present in use do not fulfill this requirement, and the object of the present invention is to provide a pie chute which will effectively guide a greater range of elements irrespective of the location of the ears thereon.

With this object in view, a pie chute according to the invention is adapted to guide the elements solely by their projecting ears and may consist of two oppositely disposed channelled members which engage the ears of the element and permit

the body of the element to extend as far as may be required, forwardly or rearwardly in relation to the laterally extending ears.

The invention is hereinafter more particularly described with reference to the accompanying drawings in which:

Figure 1 is a front elevation of a portion of a distributing mechanism provided with a pie chute according to the invention;

Figure 2 is a side elevation thereof;

Figures 3 and 4 are sections taken on the line A—A of Figure 1 showing respectively different typographical elements in the chute, and, Figures 5 and 6 are edge-views of the two forms of typographical element shown in Figures 3 and 4 respectively.

The distributing mechanism illustrated in the drawings comprises distributor screws 1 by which typographical elements 2 are conveyed along a distributor bar 3 for delivery in the ordinary way to the channels of a magazine, or in the case of typographical elements not stored in the magazine, to a flared chute 4 by which such elements falling from the end of the bar 3 are conducted to a pie chute 5.

A pie chute according to the invention consists of two members 6, 7, having oppositely disposed channels 8, by which the ears 9 of the typographical elements are engaged. In the constructional form of chute illustrated in the drawings, the members 6 and 7 are constituted by forwardly extending extremities of a substantial U-shaped guide plate, the rear wall 10 of which is far enough to the rear of the channels 8 to accommodate an element 2 having a body portion 11 extending the maximum distance rearwardly of the ears 9. Thus, an element 2 such as that represented in Figure 6 is accommodated in the chute in the manner shown in Figure 4, and an element 2 of the form represented in Figure 5 is accommodated in the chute with the main body portion of the element extending forwardly thereof as illustrated in Figure 3.

In an alternative construction not illustrated in the drawings, the channels 8 may be constituted by strips U-shaped in cross-section spaced apart at intervals in the length of the chute by bridge pieces U-shaped in cross-section extending rearwardly of the channels.

In carrying out the invention, the chute 4 by which the elements are conducted from the distributor bar 3 to the chute 5 is preferably formed with rails 11 at its lower end serving to direct the ears 9 of the elements, irrespective of the location of the said ears in relation to the thick-

ness of the element, into the channel sections 8 of the chute 5.

Having described my invention, I declare that what I claim and desire to secure by Letters Patent is:

- 6 1. In a typographical composing and distributing machine a pie chute adapted to guide a typographical element solely by its projecting ears comprising two oppositely disposed channelled 10 members which engage the ears of the element regardless of their setwise location and permit the body of the element to extend as far as may be required forwardly or rearwardly in relation to the laterally extending ears.
- 15 2. In a typographical composing and distributing machine a pie chute comprising a U-shaped guide plate having channels formed at the forward extremities thereof for guiding a typographical element by its projecting ears.
3. In a typographical composing and distributing machine the combination with a pie chute adapted to guide a typographical element solely by its projecting ears of a flared chute adapted to receive a typographical element from the distributor of the typographical machine and to conduct the element regardless of the setwise location of its projecting ears into the pie chute.
4. In a typographical composing and distributing machine the combination with a U-shaped guide plate having channels formed at the forward extremities thereof for guiding a typograph-

ical element by its projecting ears of a flared chute adapted to receive an element from the distributor of the typographical machine and to conduct the element regardless of the setwise location of its projecting ears into the U-shaped 5 guide plate.

5. In a typographical composing and distributing machine, the combination with a pie chute adapted to guide a typographical element solely by its projecting ears of a flared chute adapted to 10 receive a typographical element from the distributor of the typographical machine and to conduct the element regardless of the setwise location of its projecting ears into the pie chute, and means at the lower end of the flared chute 15 for directing the ears of the element into the pie chute.

6. In a typographical composing and distributing machine the combination with a U-shaped 20 guide plate having channels formed at the forward extremities thereof for guiding a typographical element by its projecting ears of a flared chute adapted to receive an element from the distributor of the typographical machine and to conduct the element regardless of the setwise location of its projecting ears into the U-shaped 25 guide plate, and rails at the lower end of the flared chute for directing the ears of the element into the channels formed in the U-shaped guide plate.

RICHARD HENRY SCOTT.
